UNITED STATES PATENT OFFICE.

JOHN EDWARD JOHNSON, OF NEWARK, NEW JERSEY.

EXTENSION-TABLE CALL-BELL.

SPECIFICATION forming part of Letters Patent No. 358,614, dated March 1, 1887.

Application filed December 10, 1886. Serial No. 221,160. (No model.)

To all whom it may concern:

Be it known that I, JOHN EDWARD JOHNSON, a subject of the King of Sweden, residing at Newark, Essex county, New Jersey, have invented certain new and useful Improvements in Extension-Table Call-Bells, fully described and represented in the following specification and the accompanying drawings, forming a part of the same.

10 The object of this invention is to connect a movable dining or library table detachably with a bell outside of the apartment by electrical connections through the floor of the room, the construction permitting the table when not in use to be moved to any part of the room, for sweeping the floor or removing the carpet.

15 The invention also includes means for applying a push-button to either or both ends of an extension dining-table by electrical connections adapted to operate upon the sliding bars of the extension-frame, whether closed or extended.

20 In the drawings, Figure 1 is a plan of an extension dining-table inverted and extended, with four leaves inserted. Fig. 2 is a vertical section of the table on line $x-x$ in Fig. 1. Fig. 3 is a vertical section upon a larger scale of the floor-bushing and cable-plug. Fig. 4 is a plan 25 of the same. Fig. 5 is a perspective view of the plug i . Fig. 6 is a diagram showing the extension-bars of a table provided with sliding electrical connections, and Fig. 7 is an edge view of the same.

30 a a represent the end legs, and a' the middle legs, of an extension-table, to which the invention is shown applied.

35 b b' is the top of the table, exclusive of the extension-leaves c . d d' are the sliding extension-bars, which are secured to the top b b' and to a tie-piece, b^2 , to which the center legs, a' , are affixed. The construction for sliding such bars upon one another and retaining them together is already well known and is not shown 40 herein.

45 The table is represented upon a floor, f , having an opening, g , provided with a bushing, h , in which a tapering hole is formed to fit a removable plug, i . The plug is provided at the top with a ring, j , to withdraw it from the hole when desired, and is formed in its sides with 50 opposite grooves, k , adapted to receive the ter-

minals l of an electric circuit, the ends of the terminal wires being bent to fit within holes k' in the sides of the plug, as shown in Figs. 3 55 and 5.

The electric conductors furnishing the terminals are preferably connected with the alarm-bell B by a duplex cable, l' , which is formed beneath the floor, with sufficient slack to permit the withdrawing of the plug from the bush 60 h and the pulling of the cable through the bush to attach the terminals to the table.

In Fig. 2 binding-posts e e' are shown upon the tie-piece b^2 with such terminals attached 65 thereto by withdrawing the plug from the bush h and pulling the cable up to the binding-posts. The feet of the binding-post are shown in the drawings connected in like manner with the ends of wires o , which are extended to 70 push-buttons m m' at each end of the table. These wires or conductors are preferably made of very fine strands of flexible metal, and are sustained upon the under sides of the bars d by tacking them thereto at intervals, as at n . 75

The extension-bars are shown drawn out in Figs. 1 and 2, with the wires extended in like manner, and it is obvious that when the bars were pushed in, upon the removal of the table-leaves c , the flexible connections o would 80 hang down slightly between the tacks n , but not sufficiently to be visible from the exterior of the table.

By using the small duplex cable commonly employed for telephone-receivers, each push-button may be independently connected with the posts e e' , so as to separately close the circuit to the alarm-bell B . 85

With the construction described, it is only necessary, when the table requires moving from its normal position to sweep the floor or remove the carpet, to detach the terminals l from the posts e e' , to apply the terminals to the sides of the plug i , and to then push the cable l' through the floor and insert the plug in the 90 bush h to retain the terminals until again required.

95 It is obvious that sufficient slack may be provided in the cable l' beneath the floor to permit the moving of the table more or less 100 around the bush h , as the binding-posts would then operate to withdraw the cable from the bush when the table was moved.

An alternative construction for the connec-

tions is shown in Figs. 6 and 7, in which the terminals *l* are applied directly to posts upon the bars *d d'*, and the conductor along the bars is formed of two series of stationary wires, with 5 links adapted to slide thereon. By this construction the cable *l'* hangs from the bars to the floor and permits a very free movement of the table in the vicinity of the bush *h*. The connections on the bars are formed by attaching longitudinal wires *s* rigidly at each end to the bars, as at *s'*, with the intermediate portion a sufficient distance from the bar for a link, *t*, to slide thereon, the link being affixed to one of the wires or applied loosely to both, 10 as may be preferred.

A binding-post, *u*, is attached to one end of each opposite series of wires upon the bars *d d'*, and the opposite ends of the wires are connected by conductors *v* with a push-button, 20 *m*², which completes the circuit along the opposed sets of bars and through the terminals *l* and cable *l'* in the desired manner.

Having thus described my invention, it will be seen that it affords the means of maintaining the electrical connections with the floor along the extension-bars *d d'*, and that it requires no adjustment to operate successfully when the table is pushed in or extended in the ordinary manner. It also affords a connection 25 by which the table may be moved within certain limits around the point of connection in the floor, and a means for quickly detaching the connections from the table and burying them in the floor when the carpet requires 30 cleaning or removal.

To avoid the loss or mislaying of the plug *i* when the cable *l'* is drawn through the bush, a notch may be made in the side of the plug, as at *k'* in Fig. 4, for the cable to pass through, 40 and the plug may thus be retained in the bush until it is required to hold the terminals *l*, as shown in Fig. 3.

Having thus set forth my invention, what I claim herein is—

45 1. The combination, with a movable table, of a push-button affixed to the same, electrical connections attached to the same and to the under side of the table-top, and a flexible connection suspended from the under side of the 50 table to the floor and extended through the same to connect with an electric circuit and alarm-bell, substantially as shown and described.

2. The combination, with the movable table, 55 of a push-button and electrical connections provided with binding-posts affixed thereon, an aperture through the floor sustaining the table, and an electrical cable connected with an electric circuit and alarm-bell and movable 60 through such floor-aperture to connect its terminals with the said binding-posts and

push-button, substantially as shown and described.

3. The combination, with a movable table having a push-button, electrical connections, 65 and binding-posts thereon, of an aperture in the floor and a duplex cable connected with a bell and electric circuit, and movable through such floor-aperture to permit its attachment to the binding-posts and the movement of the 70 table about such aperture, substantially as shown and described.

4. The combination, with a movable table having a push-button, electrical connections, 75 and binding-posts thereon, of an aperture in the floor provided with a tapering hole and a removable plug fitted to such hole and adapted to retain the terminals of two electric conductors therein when not in use, substantially as shown and described.

5. The means for sustaining the electric terminals when detached from the table, consisting in the floor-bush *h*, provided with tapering hole, and the plug *i*, provided with means for drawing it from the hole, and formed with 85 grooves *k* and holes *k'*, to retain the terminals therein, substantially as shown and described.

6. The combination, with an extension dining-table, of a push-button and electric conductors connected therewith and secured upon 90 the bars *d d'*, and adapted to maintain their electric connections with an external circuit, and with the push-button, when the bars are pushed in or extended, substantially as herein set forth.

7. The combination, with an extension dining-table, of an electric circuit and bell connected by wires through the floor with the under side of the table, separate push-buttons at opposite ends or sides of the table, and separate conductors arranged, substantially as described, for forming an independent circuit upon the table from each push-button to the alarm-bell, substantially as shown and described.

8. The combination, with an extension dining-table having bars *d d'*, of a push-button located thereon, electric connections extended from an alarm-bell and an electric circuit to the under side of the table, the wires, *s* affixed upon the extension bars *d d'*, and the links *t*, connecting such wires and adapted to slide thereon, the whole being arranged and operated substantially as herein set forth.

In testimony whereof I have hereunto set 115 my hand in the presence of two subscribing witnesses.

JOHN EDWARD JOHNSON.
